UNITED STATES PATENT OFFICE.

GRANVILLE M. BREINIG, OF NEW MILFORD, CONNECTICUT.

WOOD-FILLER.

SPECIFICATION forming part of Letters Patent No. 410,144, dated September 3, 1889.

Application filed February 27, 1889. Serial No. 301,341. (No specimens.)

To all whom it may concern:

Be it known that I, GRANVILLE M. BREINIG, a citizen of the United States, residing at New Milford, in the county of Litchfield and State of Connecticut, have invented a new and useful Improvement in Wood-Fillers, which is fully set forth in the following specification.

The object of my invention or discovery is to perpetuate the consistency of compounds known as "wood-fillers" and the like when composed of silex ground in linseed or other oils with japans and "driers," so called, which are put up for sale in various-sized sealed packages, ranging from a pound to a barrel. It is equally efficacious, however, in putting up white and red lead, paints, and almost any preparation that has a tendency to consolidate by standing. Such compounds, especially silex, when ground into paste, having the oils and driers in combination, are sure in time to settle and gradually become so hard as to make it almost impossible to so effectually stir as to secure the proper and relative mixing of the several ingredients which originally obtained, and to which was due in great meas-

ure the benefit and efficiency which resulted from their adaptability to fill and keep filled the pores of wood and maintain unimpaired the high polish of which the surface thereof is then susceptible. Before the article is used it is ordinarily thinned with turpentine or oil. The ingredient which settles is invariably the principal one necessary to a perfect filler. It is essential to prevent this hard settling, and this is what I claim to accomplish by the compound now to be described. The difficulty is radically overcome by mixing with the silex, likely to separate after grinding in oil by long exposure before use, one part of finely-ground meal of wheat with thirty parts of silex.

What I claim, and desire to secure by Letters Patent, is—

A compound for wood-filling, containing silex ground in oil in combination with ground meal, in proportions substantially as specified.

GRANVILLE M. BREINIG.
